Design for Six Plate Stove.

N. S. Vedder & Fanny Ripley

Troy, N.Y.

Dec. 1389

N. S. Wedder & Ezra Ripley, of Troy, N.Y.
Assignors to N. S. Wedder.
Whole No. 1389. Letters Patent No. 24. Dated May 5, 1861.

The schedule referred to in these Letters Patent and making part of the same.

To all whom it may concern:

Be it known that we, N. S. Wedder and Ezra Ripley, of Troy, in the County of Rensselaer, and State of New York, have invented or produced a new and useful design for a "Six plate heating stove", and we do

hereby declare that the following is a full, clear, and exact description of the same, reference being had to the annexed perspective drawing and to the letters of reference marked thereon, forming part of this Specification.

The description of our design for six plate stove is as follows:

viz: A' is the top plate, having the raised panel A, and the mouldings (a). B, is the side plate with the ornamental scrolls, C. C, and centre ornament D. E is the fire door with the ornament E, upon its panel, G, is the front plate, I, is the bottom plate with the moulding H, around it. H, is the leg with the shell ornament I, upon its face.

Having fully described our design for a six plate stove.

What we claim as new and desire to secure by Letters Patent is:

The ornamental design and configuration of stove plates, such as herein described and shown in the annexed perspective drawing.
